CONTROL FOR A MICROPHONE

Filed June 21, 1926

INVENTOR
A. L. Bower.

UNITED STATES PATENT OFFICE.

ABRAM L. BOWER, OF SOUDERTON, PENNSYLVANIA.

CONTROL FOR A MICROPHONE.

Application filed June 21, 1926. Serial No. 117,631.

The purpose of this invention is to control the relation of the microphone to the broadcaster from a more or less remote point, preferably from the vicinity of a loud speaker. The inventor has observed that the manager of a broadcast studio made frequent trips from the studio to the side of a large 5 loud speaker and returned to prompt the broadcaster in case his relation to the face 10 of the microphone was not quite right.

The drawing illustrates one embodiment of the invention. In the drawing F represents the frame or front of the microphone and I do not propose to move this by remote 15 control. F may be a plain ring of sufficient size to keep the attention of the broadcaster. Mi is the microphone proper. It is supported on the top of a vertical shaft or axis S but it may be supported on a horizontal 20 shaft instead. Shaft S also carries an insulated contact arm 35 which rides over a number of brass contact plates 34, 32, 30, 28, 26, 24, 22, 20, 18 when the microphone 25 Mi is rotated so that its plane forms a more or less acute angle with the plane of frame F. Shaft S carries a gear G near its lower end and this gear G engages a worm gear W operated horizontally by a shaft 15 connected to a reversible motor Mo.

The microphone is connected by wires 40 and 41 with an amplifying set RS containing the usual batteries and equipment. The output of the amplifying set RS is connected to the loud speaker L S by wires 42 and 43. This loud speaker is placed at any desired point, preferably in a room adjoining the studio.

The motor Mo is controlled by a key or switch K and a pole changer 7 and is energized by a battery 1 or other generator of 40 electric current. This wiring may be simplified by making the field magnet Fi of the motor a permanent magnet and providing for the reversal of the current direction 45 through the armature Ar of the motor Mo.

The circuit to the armature is as follows:—from battery 1, to wire 2, key K, contact 3, contact 4, wire 5, armature Ar and wire 6 to the battery. The circuit to the 50 field Fi is as follows:—from the battery 1, to wire 2, key K, contact 3, contact 4, wire 5, arm 12, contact 11, wire 10, field Fi, wire 9, contact 8, arm 7 and wire 6 to the battery. By throwing the pole changer to its lower

position the motor will be reversed because 55 the current supply in the field winding Fi will be reversed.

The gear reduction between the worm W and gear G should be considerable. The drawing does not show the full gear reduction 60 desired.

In starting the broadcasting, the microphone may be turned to the position shown. In case the microphone suffers a jar from the voice of the broadcaster, key K is pressed 65 causing the motor to deflect the microphone plane still further. When the result is pleasing, the key is released.

However if the result is weak and greater volume is desired the amplification may be 70 increased or the pole changer may be reversed and the key again be pressed down until the force of the broadcaster's voice is 75 right. The key is then raised. It is understood that the key may be provided with a spring to open the circuit to the motor when the pressure is removed from the key.

An ammeter or other current gauge A M is placed near key K and the loud speaker L S. Resistances 33, 31 etc., are connected 80 to adjacent brass plates 33, 31, 29 etc. The circuit of the gauge is as follows,—from the battery 16, to brass contact 18, resistance 19, contact 20, resistance 21, contact 22, resistance 23, contact 24, resistance 25, contact 26, 85 resistance 27, contact 28, resistance 29, contact 30, arm 35, wire 36, gauge Am, and wire 37 to the battery 16. The reading of the gauge is in degrees to correspond with the angle to which the microphone is turned. 90 Various modifications of this invention may be made without departing from the spirit and scope thereof.

I claim:—

1. The combination of a microphone with 95 a remote control and means for varying the relation of said microphone to the broadcaster, said remote control controlling said means.

2. A microphone mounted on a shaft and 100 adapted to be moved thereby, a motor to operate the shaft and an electric circuit including the motor.

In witness whereof, I have signed this specification this nineteenth day of June, 105 1926.

ABRAM L. BOWER.
